G. A. F. JOHNSON.

GRAIN CAR DOOR.

APPLICATION FILED APR. 17, 1920.

1,358,373.

Patented Nov. 9, 1920.

By Watson E. Coleman,
Attorney

UNITED STATES PATENT OFFICE.

GUST A. F. JOHNSON, OF NEWMAN GROVE, NEBRASKA.

GRAIN-CAR DOOR.

1,358,373.

Specification of Letters Patent.

Patented Nov. 9, 1920.

Application filed April 17, 1920. Serial No. 274,676.

To all whom it may concern:

Be it known that I, GUST A. F. JOHNSON, a citizen of the United States, residing at Newman Grove, in the county of Madison and State of Nebraska, have invented certain new and useful Improvements in Grain-Car Doors, of which the following is a specification, reference being had to the accompanying drawings.

10 This invention relates to an improved grain door for use in connection with grain cars, trucks and the like, and an object is to provide a device of this kind, which is very simple, efficient and practical in construction and capable of being cheaply made and sold and applied to a car at a reasonable profit.

Another object consists in the provision of a device of this kind, wherein the grain door is slidable into a closed position, in combination with a single loop lever adapted for moving the door into and out of closed position and adapted to be engaged by a latching member, for holding the door locked.

Still another object consists in the provision of guides, with which the door engages, in combination with inclined flanges overlying the opposite side edges or flanges of the door (which are beveled or inclined correspondingly to the flanges of the guides) so that the door may wedge into locked position.

A further object embodies a flange across the lower portion of the door opening extending from one overlying flange of one of the guides to the opposite flange of the other guide, to act as means to prevent escape of the grain when the door is closed.

While the design and construction at present illustrated and set forth is deemed preferable, and it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be hereinafter set forth, shown in the drawings and claimed.

In the drawings:

Figure 1 is a view in side elevation of a portion of a grain car, showing the improved grain door as applied thereto, showing the door in closed position,

Fig. 2 is a view in side elevation of the side of a truck body, showing the improved door as applied, and showing the door in an open position,

Fig. 3 is a vertical sectional view on line 3—3 of Fig. 1, showing the door closed and locked,

Fig. 4 is a sectional view on line 4—4 of Fig. 2, showing the door open, a portion of the single actuator being engaged by the upper part of the door, so as to act to open the door a substantial distance, and

Fig. 5 is a detail perspective view of the lower end of one of the vertical side angle irons 3 showing how the inclined bent portion 8 is formed.

Referring more especially to the drawings, 1 designates a portion of a grain car which is provided with a grain door opening 2. Extending vertically of the side of the car and adjacent the side jambs of the door opening are angle members 3, which are arranged in order to form guides for the grain door. An angle iron 4 is arranged in a horizontal position and is secured to the side of the car as at 5 so that one of the flanges thereof will act as a cover or shed, to deflect the rain and the like from the door.

The lower portions of the vertical angle irons 3 are bent upon themselves as shown at 6 and in order to accomplish this the lateral flanges 7 of the guide angle irons are cut as shown at 8, thereby permitting the lateral flanges of those portions of the guides which are bent to overlie or overlap the lateral flanges of the vertical fixed portions of the angle irons. It will be noted that the bent portions 9 of the side angle irons are inclined, and in order to attain this result, the lateral flanges of the fixed portions of the vertical guides are beveled off or inclined where they are cut at 8, whereby the bent portions 9 may engage therewith. The lateral flanges of the best portions 9 are bolted or riveted or otherwise secured at 11 to the lateral flanges of

the fixed guides in order to insure a rigid construction and so that the bent portions 9 may act as abutment means, with which parts of the grain door are designed to 5 wedge, when the door is closed.

5 The protecting angle iron is secured to the lower part of the car, and overlies the lower portion of the door opening and the inclined bent portions 9, in order to insure a 10 rigid construction. This protecting angle iron 12 is secured at 13 to the car, and the flange 14 is disposed or bent in order to be engaged by the door to insure a firm position of the door when closed. The vertical angle irons 3 are secured at 15 to the side of 15 the car.

A door actuating member or lever loop 16 is provided and it is constructed from a single length of rod material bent upon 20 itself to form the loop 17, the side arms of which have lateral parts 18. Beyond the lateral parts 18, the arms of the loop are extended in parallelism, and in alinement with the arms of the loop as shown at 19. 25 The ends of the portions 19 are bent laterally to provide the trunnions 20, which are fulcrumed in bearings 21 of the lateral flanges of the vertical guides or angle irons 3 so that the lever loop may be moved pivotally 30 for the purpose of opening and closing the door. A grain door 22 is provided, and this door comprises a frame having side angle pieces 23 and transverse pieces 24 and 25, which are riveted together and to 35 which a sheet metal plate 26 is riveted, as shown. The vertical side edges of this sheet metal plate 26 are spaced from the lateral flanges of the frame of the door, a distance so that the plate may engage between the 40 edges of the flanges of the bent portions 9 to assist in reinforcing the door. In other words, the sheet metal plate 26 is of a width sufficient to set between the edges of the flanges of the bent portions 9. Metallic 45 loops 27 are secured at 28 to the door and these loops are in turn pivotally mounted on the lateral parts 18 of the loop lever so that when the lever is moved upwardly, the door may be withdrawn from its guides, and 50 when the loop is moved downwardly, the door will be moved to a closed position, and when moved to a closed position, the beveled edges 29 of the lateral flanges of the side angle irons of the door will wedge into 55 contact with the flanges of the bent portions 9, and insure holding the door in a rigid closed position, and the lower part of the sheet metal plate 26 will also wedge in contact with the flange 14 of the protecting angle strip.

60 Pivoted on the metal plate 26 as at 30 is a rotatable button or plate 31 provided with an arm 32. The arm 32 is designed to overlie the lever loop, when swung to a down-

ward position and the door closed in order 65 to hold the door in a closed position and in a wedged contact with the bent portions 9 and the flange 14. When it is desired to open the door it will be noted that the button may be rotated on its pivot in order to move the 70 arm 32 from a position over the lever loop, in which case the lever is free to be swung upwardly on its fulcrum. It will be noted that the portions of the arms of the lever loop between the trunnions 20 and the bent 75 portions 18 will be so disposed with relation to the upper edge of the door that when the lever is moved on its fulcrum for the purpose of opening the door, the upper edge of the door will contact with the portions 80 of the arms between the parts 18 and the trunnions 20 so that upon further movement of the lever loop, the door may be swung entirely open in an upward direction.

When the door is so opened it will assume 85 a position at right angles to the lever loop. It will be observed that the door may be opened as above stated and then the loop may be closed against the outer face of the door and locked in such a position so that 90 the door may swing outwardly and upwardly with the lever loop, in fact the two will move together as one body. This arrangement and operation of the door is only attained when the lower edge of the door 95 has been disengaged from the bent portions 9 of the lower ends of the angle irons 3. When the door is so used, it will swing against the outer portions of the bent portions 9 and may be tilted outwardly in order 100 to permit the discharge of grain and to permit access to the interior of the car through the grain door opening.

The invention having been set forth, what is claimed as new and useful is:— 1

1. In a grain door for grain cars and the like, the combination with a door opening, of side angle irons constituting guides secured to the sides of the door adjacent the side openings, the lower ends of said guides having bent inclined parts, a lever fulcrumed in bearings of the lateral flanges of the guides and provided with trunnions, a grain door pivotally mounted upon the trunnions of the lever and adapted to engage the guides, the trunnions of the lever being so offset from the pivots of the lever, as to constitute means to force the lower edge of the door in contact with the inclined parts of the vertical guides, when the lever is closed.

2. In a grain door for grain cars and the like, the combination with a door opening, of side angle irons constituting guides secured to the sides of the door adjacent the side openings, the lower ends of said guides having bent inclined parts, a lever fulcrumed in bearings of the lateral flanges

of the guides and provided with trunnions, a grain door pivotally mounted upon the trunnions of the lever and adapted to engage the guides, the trunnions of the lever being so offset from the pivots of the lever, as to constitute means to force the lower edge of the door in contact with the inclined parts of the vertical guides, when the lever is closed, and means carried by the door to operatively engage the lever for holding the lever locked and the door closed.

3. In a device as set forth, a grain car having a grain door opening, guides adjacent the jambs of said opening, the lower ends of the guides having inclined parts, a grain door adapted to engage said guides and having inclined edges at their lower ends, adapted to wedge in contact with the inclined parts of the guides, a lever pivoted in the upper parts of said guides and having trunnions offset from the pivots of the lever, means for pivoting the door on said trunnions, whereby when the lever is moved downwardly against the door the inclined parts of the lower portions of the door will wedge in contact with the inclined parts of the guides, and when the lever is moved upwardly and outwardly, the upper edge of the door will contact with portions of the side arms of the lever for holding the door at right angles to the lever so that the door may be opened when the lever is moved upwardly and outwardly.

4. In a device as set forth, a grain car having a grain door opening, vertical guides adjacent the sides of the door opening, and having door retaining means at their lower ends, a door to engage said guides and said retaining means, a lever pivotally mounted in the upper ends of the guides, said lever having trunnions offset from the pivots of the lever and to which the door is pivotally connected, whereby the lower portion of the door may be wedged into engagement with said retaining means when the lever is moved downwardly, and withdrawn when the lever is moved upwardly, the upper edge of the door adapted to engage portions of the sides of the lever between the trunnions and the pivot parts of the arms of the lever, so that when the lever is moved upwardly the door will likewise move and will assume a position at right angles to the lever.

5. In a device as set forth, a grain car having a grain door opening, a vertical guide adjacent the sides of the door opening, and having door retaining means at their lower ends, a door to engage said guides and said retaining means, a lever pivotally mounted in the upper ends of the guides, said lever having trunnions offset from the pivots of the lever and to which the door is pivotally connected, whereby the

lower portion of the door may be wedged into engagement with said retaining means when the lever is moved downwardly, and withdrawn when the lever is moved upwardly, the upper edge of the door adapted to engage portions of the sides of the lever between the trunnions and the pivot parts of the arms of the lever, so that when the lever is moved upwardly the door will likewise move and will assume a position at right angles to the lever, and means carried by the door to overlie the lever when swung downwardly in contact with the door to hold the lever and door locked.

6. In a device as set forth, a grain car having a grain door opening, guides adjacent the sides of the jambs of the door opening, a door engaging said guides and provided with loops at its upper end, a lever pivotally mounted in the guides and having trunnions offset from the pivots of the lever and engaging said loops of the door, whereby upon moving the lever upwardly, the door may be withdrawn from the guides, the loops of the door being so arranged relatively to the arms of the lever whereby the upper edge of the door may contact with the arms of the lever, whereby the door may be swung outwardly and assume a position at right angles to the lever when being opened.

7. In a device as set forth, a grain car having a grain door opening, guides adjacent the sides of the jambs of the door opening, a door engaging said guides and provided with loops at its upper end, a lever pivotally mounted in the guides and having trunnions offset from the pivots of the lever and engaging said loops of the door, whereby upon moving the lever upwardly, the door may be withdrawn from the guides, the loops of the door being so arranged relatively to the arms of the lever whereby the upper edge of the door may contact with the arms of the lever, whereby the door may be swung outwardly and assume a position at right angles to the lever when being opened, and means carried by the outer face of the door to hold the lever in contact with the door so that the door and lever may move as one body after the door has once been opened.

8. In a device as set forth, a grain car having a grain door opening, guides adjacent the sides of the jambs of the door opening, a door engaging said guides and provided with loops at its upper end, a lever pivotally mounted in the guides and having trunnions offset from the pivots of the lever and engaging said loops of the door, whereby upon moving the lever upwardly, the door may be withdrawn from the guides, the loops of the door being so arranged relatively to the arms of the lever whereby

the upper edge of the door may contact with the arms of the lever, whereby the door may be swung outwardly and assume a position at right angles to the lever when being opened, means at the lower portion of the door opening and connected to the guides, for retaining the lower end of the

door in place, and means carried by the outer face of the door to overlie the lever to hold the lever and the door locked. 10

In testimony whereof I hereunto affix my signature.

GUST A. F. JOHNSON.
